UNITED STATES PATENT OFFICE.

WILLIAM G. RIVERS, OF ATTLEBORO, MASSACHUSETTS.

SHAVING-MUG.

SPECIFICATION forming part of Letters Patent No. 729,417, dated May 26, 1903.

Application filed February 17, 1903. Serial No. 143,773. (No model.)

To all whom it may concern:

Be it known that I, WILLIAM G. RIVERS, a citizen of the United States, and a resident of Attleboro, in the county of Bristol and State 5 of Massachusetts, have invented a new and Improved Shaving-Mug, of which the following is a full, clear, and exact description.

This invention relates to improvements in shaving-mugs, the object being to provide in 10 the cup a simple means for holding the soap cake out of contact with the water, but so arranged that the soap may be forced into the water to wet the same preparatory to forming a lather.

15 Other objects of the invention will appear in the general description.

I will describe a shaving-mug embodying my invention and then point out the novel features in the appended claims.

20 Reference is to be had to the accompanying drawings, forming a part of this specification, in which similar characters of reference indicate corresponding parts in all the figures.

Figure 1 is a sectional elevation of a shaving or lather cup embodying my invention. 25 Figs. 2 and 3 are sections respectively on the lines 2 2 and 3 3 of Fig. 1. Fig. 4 is a bottom plan view of the cup, and Fig. 5 is a section on the line 5 5 of Fig. 4.

30 Referring to the drawings, 10 designates the cup, made of any suitable material—such, for instance, as metal or earthenware. The bottom 11 of the cup is provided with openings 12 13, which are controlled by the valve- 35 plates 14 15, connected one with the other and arranged to slide in guideways 16, secured to the under side of the bottom 11. From the valves an operating-rod 17 extends outward through an opening in the wall of 40 the cup. Movable vertically in the cup is a perforated plate 18, on which a cake of soap 19 is designed to be placed. The perforated plate 18 is supported from the bottom 11 by means of coiled springs 20. I have shown 45 four of these coiled springs; but my invention is not limited to any particular number. The lower ends of the springs connect with lugs 21, mounted on the bottom 11, and the

other ends engage with lugs formed on the under side of the plate 18. These lugs will 50 prevent lateral displacement of the springs. A portion 22 of the cup extends somewhat below the bottom 11, and this portion 22 when the cup is in use is seated in a pan 23.

In use water and soap will be placed in the 55 cup, as indicated in Fig. 1. When it is desired to dampen or wet the soap, it may be forced downward into the water by the pressure of the lather-brush on the upper side of the soap. Of course upon releasing said pressure the springs 20 will move the soap upward and out of the water. When it is desired to clean the cup, the valves 12 13 may be moved to open the ports 14 and 15, and the water will pass out through said ports, 60 65 and fresh water may be poured in at the top, which by running through the cup will thoroughly cleanse it.

By normally holding the soap out of contact with the water it is obvious that it will 70 last much longer than it would if continuously in the water.

Having thus described my invention, I claim as new and desire to secure by Letters Patent—

75 1. A mug or cup, a perforated plate therein, springs supporting said plate, the said cup having a valve-controlled opening, and a pan in which the lower portion of the mug or cup is removably seated.

80 2. A cup having an opening or openings in its bottom, slide-valves for controlling said openings, a stem extended outward from the valves through the opening in the wall of the cup, a perforated plate in the cup, springs 85 supporting said plate from the bottom of the cup, and a pan in which the lower portion of the cup may be seated.

In testimony whereof I have signed my name to this specification in the presence of 90 two subscribing witnesses.

WILLIAM G. RIVERS.
